UNITED STATES PATENT OFFICE.

T. E. C. BRINLY, OF LOUISVILLE, KENTUCKY.

IMPROVEMENT IN PLOWS.

Specification forming part of Letters Patent No. 92,698, dated July 20, 1869.

To all whom it may concern:

Be it known that I, T. E. C. BRINLY, of Louisville, in the county of Jefferson and State of Kentucky, have invented a new and useful Improvement in Plows; and I do hereby declare that the following is a full, clear, and exact description of the same, reference being had to the annexed drawings, in which—

Figure 1 is a perspective view of my improved plow as it appears when mounted upon its stock for use. Fig. 2 is a side elevation, showing the helve or standard to which the mold-board and share are attached, with the means of such attachment, and showing also the manner of attaching the stock to the helve or standard. Fig. 3 is a rear end view of the plow, showing the strengthening-ribs upon the standard and the chilled or hardened heel-piece upon the same. Fig. 4 is a side elevation of the standard, with a subsoil-share and mold-board attached thereto, and showing also a projection upon the side of the helve or standard for securing the same thereto, and the bolts which secure it in position. Fig. 5 is a plan or top view of the subsoil-share and its point. Fig. 6 is a bottom view of the same, showing the recess therein for the reception of the projection to be formed upon the helve or standard. Fig. 7 is a front view of the furrow-turning mold-board and share, showing where they are joined together. Fig. 8 is a bottom view of the same, showing the recess in the share or point for the reception of the projection upon the helve or standard. Fig. 9 is a top or plan view of the helve or standard, showing the elongated slot in its upper and forward end.

Corresponding letters refer to corresponding parts in the several figures.

A in the drawings represents the beam or stock of the plow, which may be of any approved material and construction.

B represents the handles, the arrangement of which is clearly shown in Fig. 1.

C represents the helve or standard, which has upon its upper end projecting flanges *c e* from its front and rear edges, the rear one being furnished with an aperture or hole for the reception of a bolt for securing the same to the beam, while the front one is provided with an elongated slot formed transversely within it, which slot is for the purpose of enabling the plow to be shifted upon the beam, so as to

cut a greater or less width of furrow, which may be done by loosening the nut upon the bolt which passes through the front projection and swinging the standard to the right or left upon the bolt which passes through the rear projection. That portion of the standard which extends downward from these projecting flanges consists of a plate of metal of sufficient thickness and width to give it the required strength when supported by the ribs *a a*, to sustain the mold-board and share, which are secured to its lower portion. The lower end of this helve or standard is to be supplied with elongations upon its edges, which will give it a form nearly corresponding to that shown in Figs. 2 and 4, its rear portion being supplied with a movable portion, *f*, which may be secured thereto by bolts, as shown in Fig. 4, it being made of chilled cast-iron or of steel, and hardened to prevent rapid wear. Upon the outer surface of the helve or standard a flange, *b*, is made to project, as shown in Fig. 3, for the purpose of receiving the bolts which secure the mold-board and share to the same. This standard will generally be made of cast-iron; but it may be made of wrought-iron or of steel.

D represents the mold-board, which I prefer to make of steel; but which may be made of iron, it being bent into the proper form and supplied with a hole or holes, for securing it to the projecting flange *b* of the standard C.

E represents the share or point, which may be made of steel or of cast-iron, and chilled to prevent its wearing away. It is provided upon its extreme end with a prolongation, as shown in Figs. 5, 6, 7, 8, and 9, which is at the point where it joins the share of greater thickness than such share, which thickened portion extends for some distance up upon such share, as clearly shown in the figures above referred to.

By referring to Fig. 8, which shows the mold-board and share or point as constructed of one entire piece of metal, it will be seen that upon the bottom of the thickened portion thereof a recess or groove is formed, as shown at *e* in Figs. 6 and 8, the office of which is to receive the projecting point of the front end of the helve or standard C, by which means the share or point is prevented from turning upon the standard when only one bolt is used to secure it thereto.

In Figs. 4, 5, 6, and 9 I have shown the helve or standard, which is constructed as above described, and as shown in the other figures, but which is to be supplied with a mold-board such as is shown in Figs. 4, 5, and 6, the object being to convert the plow into a subsoil-plow by removing the furrow-turning mold-board and the share or point used in connection therewith and supplying their places with the device shown in Figs. 5 and 6. This slight change, which can at any time be effected in a few minutes, it will be seen, changes a plow which is in all respects adapted for ordinary plowing into one equally well adapted for subsoil plowing, which fact is regarded as of great importance and as constituting one of the advantages incident to my invention.

Another advantage resulting from my improved construction of a plow is that by providing the helve or standard with ribs *a a*, I am enabled to make the same much lighter, and thus to reduce the weight of the plow, which necessarily diminishes the force required in drawing the same.

Having thus described my invention, what I claim, and desire to secure by Letters Patent, is—

1. The construction of the share or point *E* with its groove or recess *e*, substantially as and for the purpose specified.

2. The helve or standard *C* and the mold-boards *D*, when so arranged as to be capable of being used as a furrow-turning plow or as a subsoil-plow, substantially as shown, and for the purpose set forth.

3. The construction of the mold-board and share shown in Figs. 5, 6, and 8, they having the prolongations thereon, as shown, and the thickened portions extending along the under and upper surface thereof, substantially as and for the purpose set forth.

In testimony whereof I have signed my name to this specification in the presence of two subscribing witnesses.

T. E. C. BRINLY.
